His Attorney.

UNITED STATES PATENT OFFICE

ROLF WIDERÖE, OF KARLSHORST, GERMANY, ASSIGNOR TO GENERAL ELECTRIC COMPANY, A CORPORATION OF NEW YORK

CONTROL OF ELECTRIC SWITCHES

Application filed August 8, 1930, Serial No. 473,952, and in Germany August 16, 1929.

My invention relates to improvements in the control of electric switches, and more particularly to improvements in the control, and especially, the remote control, of circuit breakers whose opening is effected in response to abnormal circuit conditions by lockout relay means. An object of my invention is to provide improved means for controlling the circuit breakers whereby to prevent unnecessary opening of the circuit breakers by reason of failure to reset the lockout relay before closing the circuit breaker.

The releasing or tripping contacts of protective relays are in some cases so constructed that, after the response of the relay and the opening of the circuit interrupter controlled thereby, they do not automatically return to their original or normal position. For example, there are protective relays on the response of which weights are released which after traveling over a predetermined path actuate a contact to effect the opening of the associated protective switch or circuit breaker. Before the circuit breaker can be reclosed, however, the releasing or tripping contact of the relay must be opened since otherwise upon attempting to reclose the circuit breaker it will immediately be released.

In the case of remotely controlled switches, the opening of the lockout contacts of the relay before the reclosing of the switches presents difficulties. The resetting of the relay contacts must be manually effected. For this purpose an attendant must be sent to the point where the relay is located or the opening of the relay contacts must be brought about through the medium of a remote control arrangement.

Since in remotely controlled plants it is necessary that as few control lines as possible be used, any arrangement for the resetting of the relay contacts which would make it possible to get along with as small a number of remote control lines as is required for the remote operation of the switch alone would be advantageous.

According to my invention, this problem is solved in a simple manner by controlling the resetting of the relay contacts simultaneously

with the reclosing of the switch. In this case the times of the reclosing of the switch or circuit breaker and of the resetting device are so adjusted that the relay contacts leave the releasing or tripping position before the switch contacts reach the closing position. This condition can be satisfied by different arrangements. For example, the mass of the magnet core or armature in the closing mechanism of the circuit breaker can be selected relatively to the mass of the armature for the relay contacts so that the relays open their contacts in a shorter time than it takes to close the circuit breaker even in the case of the simultaneous actuation of both members. This time delay operation can, of course, be effected by the arrangement of a mechanical retardation device in the circuit breaker closing mechanism. The time interval can also be introduced electrically by providing the closing magnet of the circuit breaker with a short circuited winding or ring. With this arrangement the increase of the current in the winding of the relay which does not have the short-circuited winding takes place more rapidly than in the closing coil of the circuit breaker operating mechanism. The two arrangements described can also be combined. A time element relay can also be connected in series with the circuit closing member of the circuit breaker to effect the desired time lag.

My invention will be better understood from the following description when considered in connection with the accompanying drawing, and its scope will be pointed out in the appended claims.

The single figure of the accompanying drawing illustrates diagrammatically an embodiment of my invention as applied to the remote control of a circuit breaker 1 which is arranged to control a polyphase circuit having conductors 2. As illustrated, the circuit breaker 1 is of the latched closed type and is provided with suitable switch closing or operating means illustrated as a closing coil or winding 3.

For controlling the circuit of the trip coil 4 of the circuit breaker 1 to effect the opening thereof in response to abnormal circuit condi-

tions, there is provided a fault responsive protective relay 5 which, as shown, is of the overcurrent type and is responsive to the current in one of the phase conductors 2. While only one relay is shown, it will be understood that there may be as many as desired and the character of the disturbance to which it is responsive is immaterial so far as my invention is concerned. As illustrated, the relay 5 is of the lockout type and upon actuation of the contacts 6 is locked in the circuit closing position by suitable means illustrated as a catch 7. This catch is arranged to be released in any suitable manner herein illustrated as a releasing coil 8.

The remote control of the circuit breaker 1 is effected through a control switch 9 which, when closed on its contact 10, completes the circuit of the closing coil 3 of the circuit breaker to the control bus 11 and, when closed on its contact 12, completes the circuit of the tripping coil 4. In accordance with my invention, I so arrange the control switch that, when it is moved to circuit closing position, it 20 simultaneously energizes the circuit breaker closing means 3 and the resetting coil 8 of the lockout relay 5.

In order to introduce a time delay between the release of the lockout relay 5 and the closing of the contacts of the circuit 1, I may apply to the circuit breaker operating mechanism a suitable mass 13 whereby to introduce a greater inertia effect than that of the moving parts of the relay 5. The circuit breaker reclosing movement may also be retarded by means of a short-circuited winding 14 which delays the building up of the flux in the closing coil magnet. Both of these retarding features may be used together if desired.

Assuming an abnormal condition on the circuit 2, such as to cause the operation of the protective relay 5, this relay will close its contacts 6 and they will be latched closed by the catch 7. Upon the closure of the contact 6 the circuit of the trip coil 4 will be completed through the conductors 15, 16 and 17. When it is desired to reclose the circuit breaker, the switch 9 is moved to the left to 45 close its contact 10. In so doing, the circuit of the closing coil is completed through the conductors 18, 19, 20 and 17. At the same time the circuit of the resetting or catch releasing magnet 8 is completed through the conductors 21, 22, control switch 9 and the conductors 20 and 17. The movable member of the protective relay 5 is, therefore, released and the contacts 6 opened. Due, however, to the time lag introduced in the circuit closing movement of the circuit breaker mechanism, the contacts 6 will be opened before the circuit breaker contacts are closed. Consequently the circuit breaker will be closed after the relay 5 has been reset so that there is 60 no danger of an immediate reopening of the

breaker due to the failure of the relay contacts to be released.

It will be noted that this additional control or resetting of the protective relay means 5 is accomplished with the same number of control circuit conductors as is necessary for the opening and closing of the circuit breaker 1 so that the additional surety of releasing the lockout relay does not introduce any added expense in the way of extra conductors. This 70 is an especially important item where the remote control is located for example in a distant station.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. In combination with a latched closed circuit interrupter, operating means for closing said interrupter, means for releasing the latch of said interrupter to effect the opening thereof including a lockout relay, control means for simultaneously resetting said lockout relay and effecting the actuation of said operating means and means for effecting the movement of the contacts of the lockout relay 90 from the releasing position prior to the closing of the contacts of the circuit interrupter.

2. In combination with an electric circuit, and a circuit breaker therefor, operating means including a closing coil for effecting the closing operation of said circuit breaker, means for opening said circuit breaker in response to abnormal circuit conditions including a circuit closing lockout relay, control means for simultaneously releasing the contacts of said lockout relay from their circuit closing position and effecting the energization of said closing coil, and means for delaying the closing of said interrupter until the contacts of said relay have moved from their circuit closing position.

3. In combination with an electric circuit and circuit interrupting means for controlling the circuit, operating means for closing said interrupting means, means for opening said circuit interrupting means in response to abnormal circuit conditions including a lockout relay, means for latching said relay in a position to effect the opening of said circuit interrupting means and control means for simultaneously releasing said latching means and effecting the energization of said operating means.

4. In combination with an electric circuit and a circuit breaker therefor, operating means for closing said circuit breaker, means for opening said circuit breaker in response to abnormal circuit conditions including a circuit closing lockout relay, control means for simultaneously releasing the contacts of

said lockout relay from the circuit closing position and effecting the actuation of said operating means, and means for introducing a time delay between the opening of the contacts of the lockout relay and the closing of the contacts of the circuit interrupter.

5. In combination with a circuit breaker, means for closing said circuit breaker, means for opening said circuit breaker including a 10 circuit closing lockout relay, control means for releasing the contacts of said lockout relay from their circuit closing position and effecting the actuation of said closing means and means for delaying the closing of the contacts of the circuit interrupter until after the opening of the contacts of the lockout relay.

5
In witness whereof, I have hereunto set my hand this 15th day of July 1930.

ROLF WIDERÖE.
